UNITED STATES PATENT OFFICE.

HARRY S. DAVIS, OF INDIANAPOLIS, INDIANA.

WEATHER-STRIP.

1,352,879.

Specification of Letters Patent. Patented Sept. 14, 1920.

Application filed March 1, 1920. Serial No. 362,322.

To all whom it may concern:

Be it known that I, HARRY S. DAVIS, a citizen of the United States, residing at Indianapolis, in the county of Marion and State of Indiana, have invented certain new and useful Improvements in Weather-Strips, of which the following is a specification.

This invention relates to weather strips, especially adapted for windows of a type which includes relatively slidable sashes and in which it is desirable to provide means to prevent the entrance of dirt, air, or rain, it being among the objects of this invention to devise a weather strip which obviates the use of the ordinary parting strip, holds the sashes in alinement, reduces friction in sliding, is simple, efficient, and easy to install.

In carrying the objects of my invention into effect, I provide longitudinal, beaded members which are preferably secured to the window frame at the position of the ordinary parting strip. Corresponding, complementary, beaded members are secured to the inner side of the outer sash and to the outer side of the inner sash, respectively, coöperating with the first mentioned beaded members to provide supporting and alining means, and a weather strip for the window.

I also usually provide weather strips along the inner top edge of the outer sash and the outer bottom edge of the inner sash, these latter strips serving to close the top and bottom openings, and are in perfect alinement with the longitudinal strips, thus efficiently protecting against the entrance of air, etc. In order to prevent excessive strain on the strips I preferably secure them at such a point on the sash where the least expansion and contraction takes place, and the strips are so formed as to take up such strains at several points.

Referring to the accompanying drawings forming a part hereof and in which similar reference characters denote similar parts.

Figure 1, represents a horizontal sectional view of a portion of a window showing the construction of my longitudinal members.

Fig. 2, a partial, vertical section showing the weather strip at the top of the upper sash.

Fig. 3, a similar view showing the weather strip at the bottom of the lower sash, and

Fig. 4, a detail view showing the junction of the longitudinal and cross members.

The window 1 has the ordinary casing 2,

and if the window is an old one has a parting bead 3 for the reception of the parting strip which acts as a guide keeping the two sashes 4 and 5 in alinement. Window panes 60 6 and 7 are secured in sashes 4 and 5, respectively.

In this device the parting strip is dispensed with and a member 8 substituted therefor, said member extending transversely of the vertical trend of the sashes 4 and 5 and terminating at its edges in beads which are circular in cross section, these beads terminating in legs 9 and 10. The beads are so bent that the inner ends 70 of the legs rest against the outer face of the member 8 and in close proximity to each other, said legs from their inner to their outer ends being flared or gradually spread apart and having their extreme ends extended laterally, the lateral portions being secured to the frame 2 by means of nails 11 75 and 12 or other equivalent.

By separating the outer ends of the legs 9 and 10 the member 8 is fully reinforced 80 and braced to withstand any lateral strain directed thereagainst by the sashes 4 and 5, and when the member is being used in connection with an old frame from which the parting bead has been removed the legs 9 85 and 10 completely cover the groove in the frame from which the bead has been removed and thus excluding air and dust from passing through the groove. Coöoperating members 13 and 14 having off-set portions 90 15 and 16, respectively, are secured to the adjacent faces of the window sashes 4 and 5, respectively, by nails, or similar means, 17 and 18, the offset portions 15 and 16 resting against the faces of the sashes so that no 95 grooves or depressions are required in which to seat the offset portions. The members 13 and 14 each have a socket at one edge which closely envelop the beads on the member 8 and serve not only as a means for preventing air entering, but also to take the place of the ordinary parting strip in guiding and alining the sashes.

Along the top of upper sash 4, on the inside thereof, is secured a weather strip 19 105 by means of nails 20. A corresponding, complementary, weather strip 21 is secured to the top of the window frame by nails 22. In a similar manner weather strip 23 is secured along the outside of the bottom of 110 the lower sash by nails 24 and coöperating with weather strip 25 secured to the bottom

of the frame by nails 26. These top and bottom weather strips are so fitted that they are in substantially perfect alinement with the ends of the longitudinal strips 13 and 14, 5 as shown in Fig. 4.

By my new weather strip I obviate the use of the ordinary parting and molding strips and in old windows have a structure which protects the recess 3 from water and decay.

- 10 There is no air space left around the periphery of the window for air to enter, and the weather strip holds both sashes rigid and in alinement and eliminates friction which ordinarily occurs due to swelling 15 of the parts. The nails 17 and 18 are set at points where expansion and contraction are a minimum, and approximately midway between the edges of the sash. It requires no coring of the sash, nor special tools, nor 20 a skilled mechanic to apply my weather strip.

Having thus fully described my said invention, what I claim as new and desire to secure by Letters Patent, is:

- 25 1. A weather strip for windows comprising longitudinally placed members extending transversely between the movable parts of the window structure, the longitudinal edges of said members being formed into beads, legs integral with said beads and having their inner ends in juxtaposition to each other and their outer ends spread apart, means for securing the outer ends of
- 30

said legs to the frame portion of the window structure, and coöperating members attached to the faces of the movable members of the window structure, said coöperating members having sockets thereon adapted to closely envelop the beads of said transversely extending members.

2. In a weather strip construction the combination with a window structure including a frame and an upper and lower sash, of a member extending longitudinally of the frame and transversely between said sash, beads at the longitudinal edges of said member said beads being circular in cross section, legs integral with said beads and substantially at right angles to said member, said legs flaring outwardly from their inner to their outer ends for bracing and reinforcing said legs, means for attaching said legs to said frame for forming a stationary reinforced separating strip, and coöperating members attached to the meeting surfaces of said sash, said coöperating members having sockets formed thereon for receiving and surrounding said beads.

In witness whereof, I have hereunto set hand and seal at Indianapolis, Indiana, this 28th day of February A. D. nineteen hundred and twenty.

HARRY S. DAVIS. [L. S.]
